UNITED STATES PATENT OFFICE.

JOHN M. MARMON, OF ZANESFIELD, OHIO.

BUGGY-TOP.

SPECIFICATION forming part of Letters Patent No. 792,837, dated June 20, 1905.

Application filed December 15, 1904. Serial No. 236,981.

To all whom it may concern:

Be it known that I, JOHN M. MARMON, a citizen of the United States, residing at Zanesfield, in the county of Logan, State of Ohio, 5 have invented certain new and useful Improvements in Buggy-Tops; and I do hereby declare the following to be a full, clear, and exact description of the invention, such as will enable others skilled in the art to which it appertains 10 to make and use the same.

This invention relates to buggy-tops, and has for its object to provide a top equipped with a back-curtain arranged in such a way that it may be readily and quickly moved 15 into or out of position to close the rear opening of the top.

Other objects and advantages will be apparent from the following description, and it will be understood that modifications of the 20 specific construction shown may be made and any suitable materials may be used without departing from the spirit of the invention.

In the drawings forming a portion of this specification, and in which like numerals of reference indicate similar parts in the several 25 views, Figure 1 is a side elevation of a buggy-top provided with the present invention. Fig. 2 is a view showing the interior of the top with the top folded. Fig. 3 is a view of the 30 under side of the top with the inner covering removed. Fig. 4 is a rear elevation. Fig. 5 is a section taken longitudinally of the front brackets. Fig. 6 is a section through one of the spring-drums. Fig. 7 is a section 35 on line 7 7 of Fig. 3.

Referring now to the drawings, there is shown a buggy-seat 5, to which the present top is pivoted in the usual manner. The top comprises the usual side pieces 6, collapsible 40 top-braces 7, and cover 8.

A rod 9 is provided having its end portions bent at an angle thereto, as shown at 10, and again at an angle and parallel to its central portion, as shown at 11. These end portions 45 11 are provided with perforations, as shown at 12, and in these perforations are engaged

bolts 13, by means of which the ends of the rod 9 are secured to the rearmost bow 9' of the top, with the central portion of the rod 9 in spaced relation to the cover. 50

Secured to the foremost bow of the top 9^a are the outer ends of angular brackets 14, the inner end portions of which lie in spaced relation to the cover, and to these angular brackets are pivoted the forward ends of collapsible guides 15, which also lie in spaced relation to the cover. These guides 15 each consists of a plurality of pivoted sections 16 and at their rearward ends are pivoted to the rod 9. In the drawings the guides are illustrated as comprising four of these sections 16 each, the sections being hinged together in pairs, the inner section of each pair being pivoted to angular brackets 17, secured to an intermediate bow 9^b. At the point of pivotal 60 connection of each of the pairs of sections 16 one of these sections has one of its corners bent inwardly over the other section, so as to prevent alinement of the two sections, for a purpose to be presently described, the bent 65 corners being shown at 18.

Secured at their upper ends to the cover 8 of the top and at their lower ends to the back of the seat 5 are the back-straps 19 of the top, and secured to the outer faces of these straps 75 19 are other straps 20, the inner edges of which are left free, so that there are formed guides 21 by the straps 19 and 20, and these guides form continuations of the space between the guides 15 and the cover 8. 80

Disposed in the guides 21 are the side edges of a curtain 22, the upper edge of which projects above the rod 9, and secured to the lower corners of the curtain 22 are the outer ends of bands 23, which are connected with the 85 spring-drums 24, secured to the back of the seat 5, and which are arranged to hold the curtain yieldably at the downward limit of its movement. Secured to the curtain 22 adjacent to its upper edge is a knob 25, which is of sufficient proportions to prevent its passage 90 through the space between the central portion

of the rod 9 and the cover, so that this knob prevents disengagement of the upper end of the curtain from the cover.

In use if it is desired to raise the back-curtain 22 the knob 25 is grasped and the curtain is moved upwardly to lie upon the guides 15, in which position it is held by a hook 26, carried by the foremost bow 9^a of the top, and which is engaged with the knob 25.

10 The collapsibility of the guides 15 permits the top to be crushed back in the usual manner, and the bent corners 18 prevent alinement of the sections 16 and remove any possibility of these guides interfering with the crushing 15 of the top, as will be readily understood.

What is claimed is—

1. The combination with a collapsible buggy-top, of forwardly and rearwardly extending collapsible guides secured to the under face thereof, a curtain arranged to lie at times upon the guides, and at times to extend downwardly from the rearward edge of the top, means for holding the curtain yieldably in its last-named

position, and means for holding the curtain in its first-named position against the action of 25 the first-mentioned holding means.

2. The combination with a buggy-top, of guides secured to the under face of the top, a curtain arranged to lie at times upon the guides, and at times to extend downwardly from the 30 rearward edge of the top, guides for the side edges of the curtain when in its last-named position, a rod secured to the rearward edge of the top, and a handle carried by the curtain and by which it may be moved from its last-named to its first-named position, said handle being arranged for coöperation with the rod to prevent disengagement of the upper edge of the curtain from the rearward edge of the top.

In testimony whereof I affix my signature in presence of two witnesses.

JOHN M. MARMON.
